(57) **CLAIM**

We claim the ornamental design for a saw blade, as shown and described.

DESCRIPTION

The file of this patent document contains at least one drawing executed in color. Copies of this patent document with color drawings will be provided by the United States Patent and Trademark Office upon request and payment of the necessary fee.

FIG. 1 is a perspective view of a saw blade according to one embodiment.

FIG. 2 is a first side view of the saw blade of FIG. 1.

FIG. 3 is a second side view of the saw blade of FIG. 1.

FIG. 4 is a top view of the saw blade of FIG. 1.

FIG. 5 is a bottom view of the saw blade of FIG. 1.

FIG. 6 is a first end view of the saw blade of FIG. 1.

FIG. 7 is a second end view of the saw blade of FIG. 1.

FIG. 8 is a perspective view of a saw blade according to another embodiment illustrated in color.

FIG. 9 is a first side view of the saw blade of FIG. 8.

FIG. 10 is a second side view of the saw blade of FIG. 8.

FIG. 11 is a top view of the saw blade of FIG. 8.

FIG. 12 is a bottom view of the saw blade of FIG. 8.

FIG. 13 is a first end view of the saw blade of FIG. 8; and, FIG. 14 is a second end view of the saw blade of FIG. 8. Portions of the saw blade shown in broken lines are included for the purpose of illustrating environment and form no part of the claimed design.
